CLAIM

The ornamental design for a lighting element for a light string, as shown and described.

DESCRIPTION

FIG. 1 is a front elevational view of a lighting element for a light string showing my new design;

FIG. 2 is a top plan view thereof;

FIG. 3 is a perspective view thereof;

FIG. 4 is a left side view thereof, the right side view being a mirror image;

FIG. 5 is an exploded perspective view thereof; and,

FIG. 6 is a perspective view thereof, shown in an environment of use.

The portions in broken lines show an environment of use and form no part of the claimed design.
